UNITED STATES PATENT OFFICE

LESLIE WATT WINNALL AND EDWARD HARRY WINNALL, OF JOHANNESBURG, TRANS-VAAL, SOUTH AFRICA

MECHANICALLY-OPERATED BELL

Application filed November 10, 1928, Serial No. 318,491, and in the Union of South Africa November 17, 1927.

This invention relates to mechanically operated bells or gongs. The invention is especially applicable for use at railway crossings and in other situations where loud-sounding warning bells are required, and which bells are usually brought into operation, automatically or otherwise, by means controlling, or opening and closing the electric circuit of the bell-actuating motor.

10 The operating mechanism or means can, if desired, be designed so as to be double acting, or so that it will operate the clapper, hammer or tongue of the bell in such a way as to strike and ring the bell at the end of its movement in both directions. To the attainment of this object the invention appertains to the bell action or mechanism for transmitting the motion from the electrical motor or other actuating means to the clapper, hammer or tongue of the bell. Such means include suitable reducing gear through which the rotary motion of the electric motor is transmitted to means actuating the bell clapper, etcetera.

25 The mechanism for operating the clapper is so designed that the clapper is thrown against and strikes the bell, and is then able to rebound and swing freely in the opposite or reverse direction for a certain distance, preferably before being re-engaged and positively moved in said reverse direction by the operating means. The actuating mechanism may be such that the clapper is positively moved in the direction of one side of the bell 35 to within a short distance of the latter and is then free to continue its movement in the same direction due to its momentum, until it strikes the bell, and thereafter is free to rebound for a certain distance before being re-engaged 40 and positively moved in the reverse direction by the operating mechanism, which will then cause it to swing or move in the direction of and in the same manner strike the opposite side of the bell.

45 The operating mechanism is preferably capable of adjustment in order to vary the extent of the free movement of the clapper (due to momentum and rebound) in both directions.

50 In the accompanying drawings we illus-

trate a practical embodiment of the invention, applied to an ordinary bell in which the operating means or mechanism actuates the clapper to strike the fixed bell at the end of its movement in both directions:

55 Fig. 1 being a sectional elevation of the bell, showing the operating mechanism in elevation, and

Fig. 2 an elevation at right angles to Fig. 1, with the bell omitted.

60 In the drawings the numeral 1 denotes a carrier or support for the bell 2 and the parts of the operating mechanism for the clapper, hammer or tongue 3, which is shown provided with two heads 4 adjustably attached to the 65 lower screw-threaded portion 5 of the clapper rod 6 by nuts 7, 8. 9 represents a stud screwed into the top of the support 1, and 10, 11, nuts for securing the bell 2 thereon.

65 A bolt or pin 12 is fixed in one side of the support 1 and provided with a smooth reduced portion 13. On the portion 13 is loosely mounted a part or member 14 into which the upper end of the clapper rod 6 is screwed and secured by a lock-nut 15. 16 and 17 are 70 washer and nut respectively for retaining the part or member 14 in position on the part 13 of the bolt or pin 12. The part or member 14 is constructed integral with an arm or lever 18 which, at its outer end, is constructed with 75 an arcuate or curved slot 19, and fitted with set screws 20, 21, at the top and bottom, which enter opposite ends of the arcuate or curved slot 19.

80 22 is another pin or bolt, fixed to the support 1 below the bolt 12, on a reduced portion of which is loosely mounted a toothed gear wheel 23; 24, 25, being washer and nut respectively for retaining said wheel 23 in position on the bolt 22. The toothed wheel 85 23 carries a pin 26, fixed at a suitable distance from its axis or centre, which pin 26 operates as a crank pin and has loosely attached to it one end of a connecting rod or link 27, the other end of which is loosely attached to the outer end of the arm or lever 18 by means of a pin or bolt 28, which is positioned and works in the arcuate or curved slot 19, between the ends of the set screws 20, 21, so that the latter can be used for effecting 90 95 100

any requisite adjustment between the one end of the connecting rod or link 27 and said arm or lever 18. 29, 30, are nut and washer respectively for retaining the one end of the link 27 on the crank pin 26, and 31, 32, are nut and washer respectively on the one end of the pin or bolt 28 for retaining the other end of the link 27 on the pin or bolt 28, while 33, 34, are nut and washer respectively on the 10 other end of the pin or bolt 28 for retaining said pin or bolt 28 in position in the slot 19.

The means for driving the toothed wheel 23 is shown consisting of a pinion 35 mounted on the inner end of a spindle 36 journaled in 15 the side of the support 1 and in a bearing 37 fixed on the base portion 38 of the support 1. 39 is a further toothed wheel fixed on the spindle 36 and driven by a pinion 40 on the driving shaft 41. If the bell action or mechanism is driven by an electric motor—indicated at 42, in dotted lines, in Fig. 1—then the motor may be connected, directly or indirectly, to the driving shaft 41.

The clapper 3 is shown constructed with 25 the two heads or hammer portions 4 for striking the bell 2 at the end of the movement of the clapper 3 in both directions. In Fig. 1 the heads 4 of the clapper 3 are shown in dotted lines in proximity to the opposite 30 sides of the bell 2, which dotted positions may represent the positions to which said heads 4 are positively moved by the operating mechanism, and the points at which they are free to swing outwards due to momentum and 35 strike the bell. Any desired adjustment of the movement of the mechanism to vary the points at which the clapper 3 is free to swing outwardly in both directions due to the momentum, is effected by adjusting the set 40 screws 20, 21, relative to the pin 28.

What we claim as our invention and desire to protect by Letters Patent is:—

1. In a mechanically operated bell, the combination with the bell, and a clapper including a clapper rod and a hammer, of means for operating said clapper including a lever mounted on a fulcrum and connected at one end to the clapper rod below the fulcrum and having a slot in the other end, a link connected to the slotted end of said lever by means 45 slidably engaging in the slot, and means for operating said link, said clapper operating means acting positively to move the clapper to a point near the bell at two opposite sides 50 thereof and then allowing it to swing freely outwards in both directions, due to its momentum, to strike the bell, as set forth.

2. In a mechanically operated bell, the combination with the bell, and a clapper including a clapper rod and hammer, of means for operating said clapper including a lever mounted on a fulcrum and connected at one end to the clapper rod below the fulcrum and having a slot in the other end, a link 55 connected to the slotted end of said lever by

means slidably engaging in the slot, and means for operating said link, the connection between the link and the lever allowing of the positive movement of the clapper, through the lever, to points near the bell, and then, 70 by relative movement of the link and lever at the point of connection, allowing the clapper to swing freely outwards, due to its momentum, to strike the bell, as set forth.

3. In a mechanically operated double-acting bell, the combination with the clapper of means which positively move the clapper to a point near the bell in both directions, and then allow the clapper to swing freely outwards due to its momentum to strike the 80 bell at two opposite points, said means including a lever attached to the clapper at one end, a link attached to the lever at the other end, the end of the link and the attached end of the lever being provided the one with 85 a slot and the other with a pin working in said slot, and the slotted member being provided with screw adjusting means to vary the length of the slot and the position thereof relative to the pin, and means including 90 a crank for operating said link, as set forth.

In testimony whereof we have signed our names to this specification.

LESLIE WATT WINNALL.

EDWARD HARRY WINNALL.
